ABRADING MACHINE

Arthur S. Johnson, Beverly, Mass., assignor to
 United Shoe Machinery Corporation, Paterson,
 N. J., a corporation of New Jersey

Application December 11, 1931, Serial No. 580,388

3 Claims. (Cl. 51—78)

This invention relates to abrading machines and is herein illustrated as embodied in a machine of the type disclosed in United States Letters Patent No. 1,078,050, granted November 11, 1913, upon the application of Elmer E. Lane. The illustrated machine, like the machine disclosed in the patent to Lane, is provided with an abrading roll and a feed roll. Machines of this type are used to perform scouring, buffing or other abrading operations upon pieces of sheet material, for example upon shoe parts such as soles, counters, box toes and the like. The illustrated machine, for example, has been used for roughing outsoles, although its use is not restricted to roughing operations.

It is an object of the invention to provide an improved machine of the type under consideration.

An operator in feeding work pieces which are of considerably less width than the length of the abrading roll is likely to feed all of them at the central portion of the roll to the neglect of the end portions, thereby causing undue wear of the abrasive at the central portion of the roll and wasting the abrasive material adjacent to the ends of the roll. With a view to overcoming this difficulty and in accordance with a feature of the invention, the illustrated machine is provided with a guide constructed and arranged to direct the feeding of work pieces which are of considerably less width than the length of the roll, and means is provided for reciprocating this work guide longitudinally of the roll to cause the feeding of successive work pieces to be directed along various portions of the length of the abrading roll.

These and other features of the invention including certain details of construction and combinations of parts will be set forth in connection with an illustrative machine and pointed out in the appended claims.

In the drawings,

Fig. 1 is a perspective view of the head of a machine embodying the present invention;

Fig. 2 is a cross-sectional view of the parts shown in Fig. 1;

Fig. 3 is a detail view in front elevation showing a part of the mechanism illustrated in Fig. 2; and

Figs. 4 and 5 are fragmentary plan views of alternative forms of abrading elements respectively.

The supporting structure of the machine consists of a frame 10 adapted to rest upon the floor and carrying at its upper end a left-hand side plate 12 and a right-hand side plate 14 which together support the operating instrumentalities

of the machine. Each of the plates 12 and 14 is provided with an internal flange 15 as shown in Fig. 1, the portion of the flange 15 which extends along the lower edge of each of the plates serving to enable its respective plate to be bolted to the frame 10. In the upper portion of each of the plates 12 and 14 is a slot 16 which extends forwardly and downwardly. Slidably mounted in each of the slots 16 is a block 18. A cap plate 20 secured to the flange 15 of each of the plates 10 12 and 14 closes the upper and rear ends of the slot 16 of its respective plate. A bolt 22 is threaded through each of the plates 20 and has a swiveled connection with its respective block 18 so that by turning the bolt 22 an adjustment upwardly or downwardly of the block 18 may be effected. Each of the bolts 22 is provided with a grip handle 24 for facilitating such adjustment and with a lock nut 26 for securing the bolt in its adjusted position. Journaled in the blocks 18 20 is a shaft 28 upon one end of which is mounted a pulley 30 driven by a belt 32. A belt tightening pulley 34 (Fig. 2) serves to maintain the proper tension in the belt 32. Mounted upon the shaft 28 is an abrading roll 36. A hand wheel 38 is secured to the shaft 28 to enable the latter to be turned to a convenient position for removing or replacing an abrasive element upon the roll 36.

Carried by each of the plates 12 and 14 respectively are bearings 40 in which is journaled a 30 shaft 42 carrying a feed roll 44 which is parallel to and closely adjacent to the abrading roll 36. The feed roll 44 consists of a metal core 46 covered by a thick cushion of rubber 48. One end of the shaft 42 carries a sprocket wheel 50 which is driven by a chain 52. Each of the flanges 15 has a portion 54 (Fig. 1) extending parallel to the slot 16 of its respective side plate. These portions 54 constitute guideways for a plate 56 upon which is secured a presser plate 58. The 40 presser plate 58 extends downwardly and rearwardly toward the bite of the rolls 36 and 44 and it is secured in the plate 56 by means of screws 60 which extend through slots 62 in the presser plate 58 whereby the presser plate 58 may be adjustable upwardly or downwardly with relation to the plate 56. The lower and forward edge of the presser plate 58 is beveled adjacent to the feed roll 44. The plate 56 may be adjusted downwardly on guideways 54 by means of a pair 45 of adjusting screws 64 each of which is threaded through one of the cap plates 20 and which bears against the upper edge of the adjacent end portion of the plate 56. A similar pair of adjusting screws 66, bearing against the lower edge of the 58

plate 56, are threaded respectively through brackets 68 mounted upon the adjacent flanges 15 and serve for upward adjustment of the plate 56. After accurate adjustment of the position of the plate 56 has been determined by means of screws 64 and 66, the plate 56 is clamped securely in its adjusted position by means of a pair of bolts 70 extending through slots in the plate 56 and threaded into the respective guideways 54.

10 Depending from each of the blocks 18 and rigidly secured thereto is an arm 72 carrying at its lower end a bearing 74 for a shaft 76. Carried upon the shaft 76 is a brush 78 provided with bristles 80 upon two diametrically opposite sectors of the brush. The brush 78 is driven by a belt 79 which engages a pulley 81 carried upon an end of the shaft 76. Secured to each of the brackets 68 and extending rearwardly therefrom is an arm 82 having formed at its rear end a split clamping lug 84 in which is threaded a stop screw 86 having a knurled head. After the block 18 has been adjusted to a desired position the stop screws 86 are turned until they engage the bearings 74 respectively. If the adjustment 25 of the blocks 18 is disturbed, as in replacing the abrasive element of the roll 36, or for any other reason, the stop screws 86 enable the position of original adjustment of the blocks 18 readily to be determined. The stop screws 86 may be securely clamped in their adjusted positions by means of clamping bolts 88 threaded through the split lugs 84.

For disposing of dust which is given off from the work in the operation of the machine there is provided a conduit having a pair of upright walls 90 and a bottom wall 92 which lead rearwardly to the intake opening 94 (Fig. 2) of a blower casing 96. A perforated delivery chute 97 extends forwardly and downwardly between the walls 90. Within the blower casing 96 is a blower having plates 98 and which is mounted upon a shaft 100 having a pulley 102 mounted upon one end thereof. A belt 104 drives the pulley 102. The blower casing 96 has an outlet 106 (Fig. 1) to which may be connected a discharge conduit for conducting the dust either outside of the building or to a dust receiver. Hinged upon the blower casing 96 is a guard 108 which is curved over the abrading roll 36. A 40 baffle plate 112 secured to the above-mentioned guard 108 extends close to the periphery of the abrading roll 36 and closes a draft between the blower casing 96 and the periphery of the abrading wheel.

55 The illustrated machine, as so far described, differs from the machine disclosed in the above-mentioned Letters Patent No. 1,078,050 in that the patented machine is not provided with the stop screws 86, the clamping lugs 84, the clamping bolts 88, and the arms 82. The guard plate, which in the patented machine is curved about the upper forward sector of the feed roll, has been omitted in the machine herein illustrated. The brush of the present machine has two sectors of bristles, whereas the patented machine has only one. Except for these differences, however, the illustrated machine as described up to this point is substantially like the patented machine. The instrumentalities for driving the belts 32, 60 79 and 104 and the chain 52 of the present machine have not been illustrated, inasmuch as they are substantially as shown in the above-mentioned Letters Patent. The chain and the various belts may of course be connected as desired to one or more sources of power.

The abrading roll 36 consists of a two-part wooden core 114 pivotally connected by means of a hinge 116. Surrounding the core 114 and overlying the hinge 116 is a sheet of canvas 118. Vulcanized upon the canvas layer 118 is a cushion 120 composed of sponge rubber. Both the cushion 120 and the canvas 118 are continuous over the hinge 116 but are interrupted at the free ends respectively of the core sections 114 so as to enable the sections to be opened and closed. In order to avoid any danger of those portions of the rubber cushion 120 adjacent to the free ends of the core 114 from becoming loose from the core under the influence of centrifugal force when the roll is rapidly rotated, each section of 15 the core has secured upon its free radial face a sheet metal clip 122 having a circumferentially extending flange 124 about which the rubber of the cushion 120 is molded. To insure a positive union between the flange 124 and the rubber, 20 perforations 125, in staggered relation to each other, are formed in the flanges through which the rubber may flow prior to its vulcanization. The rubber cover, when vulcanized, is thus positively and interlockingly bonded to the clips. 25 The radial faces of the free ends of the core sections 114 are provided with the usual prongs for holding an abrasive cover. Any of the well-known devices for securing together the two sections of a hinge roll may be employed. 30

The abrasive element upon the roll 36 comprises a sheet of emery cloth 126 (Fig. 4) which is secured in the usual way upon the periphery of the roll and which has formed in it a plurality of slits 128 which are parallel and in staggered 35 relation to each other and which, when the abrasive cover 126 is mounted upon the roll, extend circumferentially with respect to the roll. The purpose of these slits 128 is to enable the emery cloth 126 to flex to accommodate the varying 40 contours of the work, thereby insuring a uniform treatment to all portions of the surface of the work, notwithstanding variations in the thickness of the work piece.

In Fig. 5 is shown alternative forms of abrasive 45 element consisting of a sheet of emery cloth 130 having slits arranged in parallel pairs connected by cuts which run longitudinally of the roll to form tabs 132. The abrasive element 130 is so mounted upon the roll 36, with respect to the 50 direction of rotation of the roll, that the free ends of the tabs 132 will be the trailing ends. When the roll is rotated the tabs 132 will swing outwardly under the influence of centrifugal force and thus bear yieldingly upon the work. 55

It has been found that in the use of machines of this character operators tend to feed the work pieces at the central portion of the abrading roll to the neglect of the end portions thereby utilizing only a small portion of the abrading element 60 and also causing undue wear at the central portion of the brush without utilizing the bristles at each end portion. In order to avoid this difficulty there is provided a guide plate 134 of considerably less width than the length of the abrading roll and having upstanding flanges 136 which, together with the body portion of the guide plate, 65 form a channel. The guide plate 134 is supported upon and may, as in the illustrated machine, be integral with a carriage 138 which is slidably and 70 rotatably mounted upon a shaft 140 journaled in bearings formed in the brackets 68, the shaft 140 being substantially parallel to the axes of the abrading and feed rolls. Depending from the carriage 138 is a forked lug 142 which straddles 75

a bar 144 thereby preventing rotation of the carriage 138 while permitting it to move longitudinally of the abrading and feed rolls. The ends of the bar 144 are secured respectively to the brackets 68. Formed in the shaft 140 is a cam groove 146. The groove 146, as shown in Fig. 3, has two oppositely directed helical portions which cross each other and which, at each of their ends, are connected to each other by curved continuations of the groove so that the cam groove is in the form of a closed continuous curve upon the surface of the shaft 140. Slidably engaging the groove 146 is a cam follower 148 having pointed ends to enable it when following the groove 146 along one of the helical portions to cross the other intersecting helical portion without jamming. The follower 148 is swiveled upon a pin 150 secured in the carriage 138 so that rotation of the shaft 140 will effect reciprocation of the carriage 138. Secured upon one end of the shaft 140 is a ratchet wheel 152 (Fig. 1). Eccentrically mounted upon one end of the feed roll shaft 42 is a pawl 154 which is maintained in engagement with the ratchet wheel 152 by a spring 156. Each rotation of the feed roll shaft 42 will cause the pawl 154 to advance the ratchet wheel 152 so that the shaft 140 is given a slow intermittent rotation thereby imparting to the feed plate 134 a still slower and intermittent reciprocation lengthwise of the feed and abrading rolls. In this way it is evident that the operator, without any need of attention on his part, will feed the various work pieces along different portions of the length of the rolls thereby utilizing all of the abrasive element upon the abrading roll and utilizing the brush to the fullest extent. A holding pawl 158 mounted upon a stub shaft 160 in the end plate 12 prevents the ratchet wheel 152 from slipping back. The holding pawl 158 is maintained in engagement with the ratchet wheel by means of a spring 162.

In operation, the abrading roll 36 is driven at a relatively high speed and the feed roll 44 at a much lower speed. The operator presents a work piece W, which, as shown in Fig. 1, may be an outsole, to the machine using the flanged feed plate 134 as a guide. The leading edge of the work piece W first engages the presser plate 58 which directs it against the feed roll 44. The rotation of the latter causes the work piece to advance and to pass between the bite of the rolls. Many work pieces are not of uniform thickness, for instance outsoles are frequently thinner at the edge portion than at the center portion particularly at the shank. The presser plate 58 serves to embed more or less the relatively thicker portions of the work piece into the yielding cover of the feed roll thus causing the surface which is to be treated to bear more or less uniformly against the abrading roll. However, in cases where the inequalities of the work piece are pronounced, it may sometimes occur that the thicker portions of the work piece bear with greater pressure than the thinner portions against the abrading roll notwithstanding the above-mentioned action of the presser plate 58. In order to avoid excessive abrading action upon the relatively thicker portions to the neglect of the relatively thinner portions the yieldable cover 120 of the abrading roll is made of relatively soft sponge rubber, considerably softer than the material of

the feed roll 44, and the above-mentioned slits 128 or tabs 132 are provided in the emery cloth to enable it to conform readily to the contour of the work piece. The abrading roll 36 is driven at a much higher speed than the feed roll 44 and in a direction opposite to that of the feed roll so that it too assists in feeding the work, but the presser plate 58 holds the work against the feed roll 44 with such pressure that the feed of the work is entirely under control of the feed roll without danger of being dragged forwardly by the abrading roll. The brush 78 loosens the dust from the surface of the work piece by both a brushing and a beating action and the dust is removed by the above-described suction draft system. The treated work piece falls upon the chute 97 which serves to deliver it to any desired receptacle.

The improvements in the abrasive cover, which is slitted for flexibility, are not claimed herein, but are claimed in my divisional application Serial No. 30,849, filed July 11, 1935.

Having fully described my invention, what I claim as new and desire to secure by United States Letters Patent is:

1. An abrading machine comprising a driven abrading roll, means for feeding work past said roll, a guide plate having a pair of upstanding flanges which together with the body portion of said guide plate form a channel of considerably less width than the length of the roll for directing work pieces to a localized portion of the roll, and means for reciprocating said guide plate longitudinally of said roll to distribute the wear of a plurality of work pieces along the length of the roll.

2. An abrading machine comprising a shaft, driving means for said shaft, an abrading roll on said shaft, work-feeding means cooperating with said roll, a member constructed and arranged to guide to said roll a work piece of considerably less width than the length of the roll, a carriage for supporting said guide member, a shaft upon which said carriage is mounted for relative rotary and longitudinal movement with respect thereto, means for restraining said carriage from rotation as the carriage shaft rotates while permitting the carriage to move longitudinally of the carriage shaft, said carriage shaft having formed in its surface an endless cam groove extending lengthwise as well as circumferentially of the carriage shaft, a cam follower engaging said cam groove and secured to said carriage whereby the rotation of the carriage shaft will cause reciprocation of the carriage, a ratchet wheel on said carriage shaft, a pawl driven by said abrading roll shaft and in driving engagement with said ratchet wheel to drive said carriage shaft, and means for preventing back slip of said ratchet wheel.

3. An abrading machine comprising a driven abrading roll, a driven feed roll cooperating with said abrading roll, said rolls being closely adjacent to each other for pressing a work piece between them, means for adjusting one of said rolls toward and from the other, and stop means adjustable independently of said adjusting means to prevent the adjustment of said adjustable roll toward the other roll beyond a position determined by a prior adjustment, thereby predetermining the desired position for subsequent adjustments.
